BURNISHING DEVICES AND METHODS

Dale L. Schubert, Tacoma, Wash.

Application August 23, 1952, Serial No. 305,961

3 Claims. (Cl. 144—309)

This invention is concerned with a process of finishing the edge of dense fiberboard by burnishing it and with various devices which may be utilized to accomplish this result.

Dense fiberboard, having a density approaching or exceeding 1, frequently called hardboard, has at least one of its faces, and sometimes both, of very smooth, hard, and frequently polished character, whereas the central portion of the board's thickness usually is comparatively soft. When the edge of such hardboard is trimmed in the final stages of its manufacture to provide a straight and clean edge, the lack of uniformity in density over the thickness of the sheet becomes apparent. To one not familiar with the method of manufacture and characteristics of hardboard, such lack of uniformity in texture of the edge of the hardboard sheet makes it appear that the product lacks uniformity and is therefore of inferior quality.

The principal object of the present invention, therefore, is to finish the trimmed edge of a hardboard sheet by burnishing it so as to have a hard, smooth, polished texture, and dark color closely comparable to the texture of at least one principal face of the sheet to provide an attractive and uniform appearance of all exposed parts of the sheet.

A further object is to densify and seal the relatively soft central portion of a hardboard sheet at the edges so as to reduce the possibility of moisture penetrating into the central portion of the sheet. In thus densifying the edge of a hardboard sheet it is an object, where desired, to bevel the sheet edge slightly to provide an under bevel viewed from the face of the sheet, so as to enable similarly trimmed and finished edges of adjacent sheets to be butted together very tightly.

In the production of such a finished edge an object is to accomplish the trimming and densifying in a single operation, or at least in immediately sequential operations, so as not to increase the fabricating cost of the hardboard by additional handling and processing.

The foregoing objects can be accomplished by relatively inexpensive mechanism which can be operated economically.

Advantages of representative devices shown in the drawings which can be utilized to perform the process of the invention are discussed in the detailed description which follows.

Figure 1 is a somewhat diagrammatic plan view with parts broken away of mechanism suitable for accomplishing the process of the present invention, and Figure 2 is an edge view of such mechanism having corresponding parts broken away. Figure 3 is an enlarged fragmentary vertical sectional view through a portion of a trimming and burnishing element, and a piece of fiberboard on which it is operating.

Figure 4 is a top perspective view of a fragment of hardboard, showing a partially trimmed edge. Figure 5 is a sectional view through edge portions of adjacent hard-

2

board sheets in abutment, taken in a plane perpendicular to the abutment line.

Figure 6 is a fragmentary face view, and Figure 7 is a transverse sectional view through another type of edge trimming and burnishing element.

Figure 8 is a fragmentary face view, and Figure 9 is a transverse sectional view through a further type of edge trimming and burnishing element.

Figure 10 is a face view and Figure 11 is a transverse sectional view through still a different type of edge burnishing element.

Figure 12 is a somewhat diagrammatic fragmentary plan view of edge trimming and burnishing mechanism incorporating separate trimming and burnishing elements.

Figure 13 is a fragmentary plan view of trimming and burnishing mechanism incorporating separate trimming and burnishing elements in which an alternative type of burnishing element is utilized.

In the manufacture of dense fiberboard, fiber mat is consolidated in a press. As a result the edge portions of the pressed board are more or less ragged, so that it is necessary to trim them straight as a subsequent step in the manufacturing process. By such pressing operation at least one side of the board is given a smooth, hard, and more or less polished surface by contact with a press platen, and the other surface of the board may be similarly finished by engagement with the opposite press platen, or it may be pressed against a screen. In the latter case the screen engaged surface will be harder than the central portion of the board, but such surface will not be smooth or polished. In either case the central portion of the board is somewhat softer than the layers immediately adjacent to the surfaces, and if a board is simply cut in a plane transversely of the board, the softer central portion is quite apparent by its lighter color and fibrous or stratified appearance. The thicker the board, of course, the more pronounced will be the contrast between the texture of the central portion of the board and those portions adjacent to the surfaces.

By the process of this invention the edges of such hardboard panels are burnished by friction, which has the double effect of compacting and thus densifying the edges so as to seal the relatively soft central portion against the entrance of moisture, and of darkening the color substantially to match that of the board face. In fact it is not objectionable to darken the edge to a color somewhat darker than the surface, but care should be taken not to apply too much pressure, nor to apply pressure for too long a period during the burnishing operation, because of the danger of the edge being given an excessively burned appearance. Particularly to enable the proper effect to be produced on hardboards of different density, it is desirable to enable the burnishing element to be adjusted so as to vary the duration and pressure of burnishing, and usually it is satisfactory to adjust both of these factors simultaneously, that is, when less burnishing action is desired the time is shortened and the pressure is decreased, and to obtain a greater burnishing effect the pressure will be increased and the time lengthened.

Since the edges of a hardboard sheet must be trimmed after the sheet is removed from the press, it is desirable in most instances to accomplish the trimming and burnishing operations simultaneously and with the same element. In Figure 1 a hardboard sheet S which has been pressed is shown carried by any suitable conveyor 1 to a combined trimming and burnishing element, after which the sheet is received by the discharge conveyor 2. The combined trimming and burnishing element is a unitary rotary disk 3 of conventional trim saw material, such as saw steel, carried and driven by the shaft 4. Around the periphery of this disk are saw teeth 5 of the usual trim saw type,

except that the sides of the teeth adjacent to the body of the sheet S do not have any appreciable set as is evident from Figure 3. The face of the combined trimming and burnishing element adjacent to the body of the sheet S is bellied toward such sheet body, as shown in Figures 1 and 3. Preferably this belly is in the form of a spherically convex surface, the projection of which is exaggerated in Figure 1 for purposes of illustration. The hardboard sheet leading edge will be engaged first by the peripheral teeth 5 of the trimming and burnishing element to trim the edge straight, and then as movement of the sheet progresses toward the central vertical plane of the element 3, the pressure of the convex disk side against the cut edge will increase progressively to consolidate the sheet edgewise and darken and polish the edge.

The amount of pressure, and consequently the extent of the burnishing action accomplished, will, of course, depend upon the amount of bellying of the burnishing portion of the element at the location of the sheet edge. The farther toward the center of rotation of element 3 the sheet edge is located, the greater will be the pressure, and consequently the more pronounced the burnishing effect. As indicated in broken lines in Figure 2, the board supporting roller conveyor may be moved vertically to shift the sheet edge toward or away from the rotative axis of element 3. Alternatively the position of the cutting and burnishing element could be adjusted relative to the conveyor, but it is more convenient to shift the conveyor in the manner indicated. Edgewise shifting of the hardboard sheet which the bellying of the burnishing element tends to effect is resisted by clamping the hardboard sheet on the conveyors 1 and 2 by hold-down rolls 6, preferably having friction gripping surfaces.

Because of the belly in the burnishing element 3, not only will the board edge be densified, sealed, polished and darkened, but it will be inclined slightly as indicated in Figure 3. Assuming that the fiberboard is fed to the trimming and burnishing element with its finish surface up, the burnishing element will produce an under bevel to the degree of the slope of a radius on the belly side of the trimming and burnishing element. Such bevel will not be great, but will be sufficient to insure that when the edges of adjacent hardboard panels are abutted as shown in Figure 5, any slight unevenness in the edges will not leave an open seam, but the portions of the edges immediately adjacent to the finished surfaces will be tightly in contact. The polished character of each of the finished edges E is indicated by the shading of such edge in Figure 4, as compared with the fibrous character of the edge E' prior to the edge trimming and burnishing operation.

The combined trimming and burnishing element utilized in a machine of the type shown in Figures 1 and 2 may take any of several forms besides the bellied disk shown in those figures and in Figure 3. In Figures 6 and 7 the disk 7 has conventional saw teeth around its periphery, and, in fact, the disk itself may be a conventional saw. To the side of such saw disk adjacent to the body of the sheet S will be secured a burnishing ring 9 of material such as fine sandpaper or equivalent polishing material. Instead of securing a ring of such material to the side of a saw 7, the teeth 8' may be set to only one side from the disk as shown in Figure 9, and the annular portion of the disk just radially inward of the teeth may be roughened such as by knurling, as indicated at 10, or abrasive dust may be applied directly to the disk surface and secured in place by suitable adhesive.

Another way in which a conventional saw 7 with conventional teeth 8 may be modified is illustrated in Figures 10 and 11 by riveting to the side of the saw adjacent to the body of the sheet S a metal or fiber ring 11, which may be secured by rivets 12 extending through both the ring and saw. The periphery of the ring 11 may have a bevel 13 against which the edge of the hardboard sheet will bear in riding onto the face of the burnishing ring 11, so that there will be no tendency for the burnishing ring to ob-

struct forward movement of the sheet. All of the combined trimming and burnishing elements shown in Figures 6 to 11, inclusive, will be mounted in the same manner as the element 3 shown in Figures 1 and 2.

5 While it is preferred to perform the trimming and burnishing operations by the same element in the manner discussed above, it is entirely possible to perform these operations sequentially by different elements disposed in adjacent relationship in a single pass of the hardboard sheet past them. In Figure 12 the hardboard sheet S will be carried by suitable feed and discharge roll conveyors which are not shown, but would be like those shown in and described in connection with Figures 1 and 2. Such conveyors will carry the hardboard sheet in the direction indicated by the arrow, first past a conventional trim saw 14 and then past a burnishing disk 15. During such movement the sheet will be held down by suitably located hold-down rolls 6.

The burnishing disk 15 shown in Figure 12, may be of 20 steel, fiber, or other suitable burnishing material, and will be set toward the body of the sheet S from the saw 14 sufficiently to exert the desired pressure on the sheet edge. The periphery of the burnishing disk has a bevel 16 on the side toward the body of the sheet S, so that the edge of 25 the fiberboard sheet will be wedged and densified by the edge of such bevel portion without blocking movement of the sheet past such burnishing element.

The burnishing disk 15, like the saw 14, preferably turns in the direction such that its portion first engaged by 30 the edge of the fiberboard sheet is moving downward so as to press such sheet against the rolls of the supporting conveyor. Instead of mounting this burnishing disk in a rigid fashion, it is desirable to have it yieldable slightly lengthwise of its supporting shaft 17. This may be effected by securing the disk on the shaft by a nut 18 and backing the disk by a shouldered collar 19. Between the shoulder of this collar and the end of a sleeve 20 mounted on shaft 17 and held against movement lengthwise relative to it, is interengaged a spiral compression spring 21 35 which holds the collar 19 firmly against the disk 15. The amount of burnishing pressure exerted by disk 15 on the edge of the hardboard sheet S may thus be established by selecting a spring 21 having the desired stiffness.

Instead of using a burnishing disk of the type shown 40 in Figure 12, which contacts the sheet edge over a substantial distance lengthwise of it, the burnishing action may be accomplished by concentrating the pressure on the sheet edge substantially along a line. In Figure 13 the sheet edge is trimmed initially by the conventional saw 14 as described in connection with Figure 12. In this instance, however, the burnishing element is a roller 22 rotated by a suitable drive belt 23 engaging a pulley coaxial with and secured to the roller to rotate about an axis perpendicular to the plane of the sheet S. Normally such sheet would move in a horizontal plane, so 45 that the rotative axis of the roller would be vertical. Such roller turns in a direction to move its surface in engagement with the edge of the sheet in a direction opposite the direction of movement of such sheet edge, 50 as indicated by the arrows on the roller and on the sheet.

The roller 22 may be mounted to press resiliently 55 against the edge of the sheet S by a spring mounting comparable to that for burnishing disk 15 shown in Figure 12, or the degree of pressure on the edge may be varied by adjusting the position of the roller mounting 24 relative to the support 25 by clamping bolts 26 received in a slot in the supporting bar 28. The roller 22 shown in Figure 13, may be of suitable hard material such as of metal or of fiber, or of other burnishing material, as 60 may be desired. Alternatively, the rim of the roller alone 65 may be of selected burnishing material mounted on a suitable core.

The principal difference between the burnishing elements shown in Figures 6 to 13, inclusive, and that 70 shown in Figures 1 to 3, inclusive, is that while the latter

would slightly bevel the edge of the fiberboard sheet, as discussed, when the rotative axis is parallel to the sheet, the former would not produce such a bevel if the rotative axes of the burnishing elements shown in Figures 6 to 12 were placed exactly parallel to the sheet and the axis of the burnishing element in Figure 13 were exactly perpendicular to the sheet. Even with these burnishing elements, however, the densified edge of the sheet could be made slightly beveled if the rotative axis of the burnishing element were slightly tilted from the positions mentioned.

I claim as my invention:

1. The method of finishing the edge of a hardboard sheet which comprises darkening and densifying such sheet edge substantially comparable to a face of such sheet by pressing a rapidly moving hard surface against such edge, the pressure and speed of such hard surface being sufficient to burn and compact such sheet edge to effect such darkening and densifying.

2. The method of finishing the edge of a hardboard sheet which comprises darkening and densifying such sheet edge substantially comparable to a face of such sheet, and simultaneously beveling such sheet edge, by pressing a rapidly rotating hard surface against such edge, the pressure and speed of such hard surface being sufficient to burn and compact such sheet edge to effect such darkening and densifying, and the application of the hard surface being at such an angle to such edge as simultaneously to effect such beveling thereof.

5 3. A burnishing machine for burnishing hardboard, comprising means operable to support a piece of hardboard disposed substantially in a plane, a burnishing roller having a burnishing periphery rotatable about an axis extending transversely of such plane and engageable with such piece of hardboard, means operable to drive said burnishing roller rotatively at a considerable speed, means operable to effect relative movement of said burnishing roller and such piece of hardboard along such piece of hardboard, and means operable to support said burnishing roller in position pressing against the hardboard piece while rotating and for movement toward and away from such hardboard piece to alter the degree of pressure of said burnishing roller thereagainst.
